ATTORNEY.

UNITED STATES PATENT OFFICE

CHARLES R. VAN DE CARR, JR., OF DAYTON, OHIO, ASSIGNOR TO CHEMIPULP PROCESS, INC., OF WATERTOWN, NEW YORK, A CORPORATION OF NEW YORK

METHOD AND APPARATUS FOR THE CHEMICAL TREATMENT OF PULP

Application filed April 12, 1928. Serial No. 269,490.

This invention relates to the treatment of fibrous material, and more particularly to a novel method and apparatus for the chemical treatment of pulp.

In the digestion of fibrous material with chemical liquors, it is customary in unloading the digesters, to permit the same to blow directly into a blow-pit. This has disadvantages well known to those skilled in the art. It is my idea to pump the cooked pulp from a digester, after the pressure has been relieved from the latter, and to pass this pulp through a continuous washing process. In doing this, it will be found that the pulp in the digester, after some of the liquor has been withdrawn, will compact at the discharging end of the digester, to such a degree that the pump cannot pull the pulp out of the digester. In accordance with my invention, I overcome this difficulty by forcing spent liquor from the washer into one or the other or both ends of the digester for diluting the pulp mass and putting the same into fluid condition.

The primary object of the invention is to provide an improved system for the unloading of digesters without resorting to the ordinary blow pits, and in this system, the pulp is withdrawn from the digesters by means of a pump which may force the same directly to a washer, or into a pulp storage tank, from which the pulp may pass through a pulp breaker, on its way to the washer. Spent liquor from the washer is withdrawn by another pump and may be forced by the latter into one or both ends of the digester for diluting the pulp, so that it will readily flow from the digester.

With the foregoing object outlined and with other objects in view which will appear as the description proceeds, the invention consists in the novel features hereinafter described in detail, illustrated in the accompanying drawing, and more particularly pointed out in the appended claims.

Referring to the drawing, the figure is a diagrammatic view of an apparatus for use in carrying out my process.

In the drawing, A designates a pulp digester, B a pulp pump, C a pulp storage tank,

D a pulp breaker, E a vacuum washer and F a spent liquor pump. These parts are all of standard construction, but I have combined the same in a novel manner. In my system, the pulp in moist condition, after the cooking is completed, is withdrawn through a valved pipe A' by means of the pump B, and it is forced by the latter through a conduit B' into the storage tank C. It is led from the latter by a pipe C' into the drum-type pulp breaker D, from which it flows by a pipe D' into the vacuum washer E.

As heretofore mentioned, the pulp is liable to pack in the lower end of the digester during the unloading of the latter and thus halt operations, and to eliminate this objection, I withdraw spent liquor from the washer, by way of pipe E', into the pump F, which forces the same through a conduit F' into valved branches F² and F³; the first branch leading to the top of the digester, and the other branch leading into the lower portion of the digester or pipe A'.

In this way, the spent liquor may be used to keep the pulp in fluid condition, so that it may be readily withdrawn by the pump B.

When the invention is used in connection with a battery of digesters, it will be understood that the digesters may be unloaded in rotation, and under such circumstances, the washer may be continuously operated, and there will always be sufficient pulp in the storage tank C to feed the washer.

The spent liquor withdrawn from the washer E is the liquor with which the pulp has been cooked. At the end cooking point, the liquor has been drawn from the digester in sufficient amount to reduce the pulp density from 3 to 10%; then the vacuum washer further reduces the density to about 30%, but at a 10% density inside the digester, it is impossible to make the pulp flow; consequently, I propose to use a percentage of the spent liquor from the vacuum washer as an agent to dilute the pulp in the digester.

There will be times during the operation of the system when it will be unnecessary to feed the spent liquor or diluting fluid into the digester, and at such times, the fluid may

be discharged from the vacuum washer by way of the valved conduit G. The pipe E' is provided with a valve E² to permit such operation.

It may also be advantageous at certain times during the unloading of the digester to dilute the pulp mass by means of water or any other suitable anti-acid liquid, and for this purpose, such liquid may be introduced 10 into the system through a valved pipe H. A bleaching agent can also be introduced through the pipe H, so as to dilute the pulp by means of a bleaching agent, and for the further purpose of pre-bleaching.

From the foregoing, it is believed that the construction and operation of the apparatus, and the steps of the process may be clearly understood, and I am aware that changes 20 may be made in the details disclosed without departing from the spirit of the invention as expressed in the claims.

What I claim and desire to secure by Letters Patent is:

1. In the treatment of pulp, digesting 25 fibrous material and withdrawing pulp from the digester, washing said pulp, and feeding spent liquor from the washer into the pulp leaving the digester to dilute said pulp.

30 2. In pulp treatment, digesting fibrous material, discharging the material from the digester, washing the material, and feeding some of the washing fluid from the washer into the digester for diluting the material in the latter.

35 3. In a process of the character described, cooking fibrous material in a digester with chemical liquor, pumping said fibrous material from the digester, feeding the withdrawn material into a washer and washing the same, and feeding the spent liquor from the washer into the digester for diluting the material in the latter while it is being withdrawn from the digester.

40 4. In a process of the character described, cooking fibrous material with chemical liquor in a digester, pumping the material from the lower end of the digester, washing the material discharged from the digester, and feeding spent liquor from the washer to the upper and lower ends of the digester for diluting the material while it is being discharged from the digester.

45 5. In a process of the character described, cooking fibrous material with chemical liquor, pumping the material from the digester after the completion of the cooking, breaking the material discharged from the digester, washing the broken material, and feeding spent liquor from the washer into the material while it is being discharged from the digester for the purpose of diluting said material.

60 6. A pulp treating apparatus, comprising a digester, a washer, means including a

pump for withdrawing pulp from the digester and feeding the same to the washer, and means for feeding spent liquor from the washer into the digester.

7. An apparatus of the class described, 70 comprising a digester, a washer, a passage-way placing the digester in communication with the washer for feeding pulp from the digester to the washer, and means including a pump for feeding spent liquor from the 75 washer into the digester.

8. An apparatus of the class described, including a digester, a washer, conveying means including a pump for moving pulp from the digester to the washer, and means 80 for feeding spent liquor from the washer into said conveying means at a point between the digester and pump.

9. An apparatus of the class described, including a digester, a washer, means including a pump for withdrawing fibrous material from the lower portion of the digester and for feeding the same into the washer, and means including a pump for forcing spent liquor from the washer into the upper and 90 lower portions of the digester.

10. In combination, a digester, a washer, pulp conveying means including a pump for withdrawing pulp from the digester and feeding the same to the washer, a conduit 95 for feeding spent liquor from the washer, a pump interposed in said conduit, and branch pipes connecting the conduit to the opposite ends of the digester.

11. In combination, a pulp treating di- 100 gester, a pipe leading from the lower end of the same, a pump connected to the pipe for withdrawing pulp from the digester, a pulp washer, means including a pipe for feeding pulp from the pump to the washer, a conduit connecting the first mentioned pipe to the washer for conveying spent liquor from the washer into the first mentioned pipe, and a pump interposed in said conduit.

12. A combination as claimed in claim 11, 110 including a pipe connecting said conduit to the upper end of the digester.

13. In combination, a digester, a pulp storage tank, a conduit connecting the digester to the storage tank, a pump interposed 115 in said conduit, a pulp breaker, means for leading pulp from the tank to said breaker, a pulp washer, means for leading pulp from the breaker to the washer, and means including a pump for feeding spent liquor 120 from the washer into the digester.

14. A pulp treating apparatus, comprising a digester, means including a pump for withdrawing pulp from the digester, and means for pumping a diluting fluid into the 125 digester while the material is being pumped from the same.

15. In pulp treatment, digesting fibrous material, simultaneously pumping the material and cooking liquor from the digester 130

after the pressure has been released from the latter, and introducing a diluting liquid into the material and cooking liquor anterior to the pump while discharging the material and cooking liquor from the digester.

5 16. In a process of the character described, cooking fibrous material in a digester with chemical liquor, simultaneously pumping said fibrous material and cooking liquor from the digester, and diluting the material and chemical liquor with liquid while pumping the same from the digester.

10 17. In a process of the character described, cooking fibrous material under super-atmospheric pressure in a digester, releasing the pressure, then simultaneously pumping the material and cooking liquor from the digester, and diluting the material and cooking liquor while it is being pumped.
